UNITED STATES PATENT OFFICE

2,168,830

BEACH PARASOL ANCHOR

Jerome B. Schroth, Santa Ana, Calif.

Application October 17, 1938, Serial No. 235,510

2 Claims. (Cl. 248—44)

This invention relates to anchor devices of the type adapted for anchoring a post in the ground, and the primary object of the present invention is to provide an anchor of this character particularly adapted for application to the end of a beach parasol post for anchoring said end of the post in the ground and thereby secure the parasol in a rigid position without any danger of it being affected materially by strong winds and the like.

The invention together with its objects and advantages will be best understood from a study of the following description taken in connection with the accompanying drawings wherein:—

Figure 1 is an elevational view illustrating the application of the invention.

Figure 2 is an enlarged detail elevational view showing the device as applied to the pointed end of the post or pole of the beach parasol.

Figure 3 is a top plan view of the anchor.

Figure 4 is an enlarged fragmentary detail view partly in section and partly in elevation showing certain details hereinafter more fully referred to.

Figure 5 is a sectional view taken substantially on the line 5—5 of Figure 2, and

Figure 6 is a perspective view of an extension sleeve hereinafter more fully referred to.

Referring more in detail to the drawings it will be seen that in accordance with the present invention the same, in the preferred embodiment thereof, comprises a stock or shank 5, the material of which to form the anchor member proper is coiled into screw form 6 with a pointed terminal 7. The screw 6 and stock 5 are connected together through the medium of two intimately positioned coils 8 which serve to reinforce or strengthen the anchor at this point and which also receive, as shown, the pointed end of the pole or post 9 of the beach parasol or umbrella 10.

Welded, or otherwise secured as at 11 to the shank or stock 5 is a split resilient clamp 12 that is adapted to embrace the pole or post 9 above the coils 8 and is contracted about the pole or post 9 to securely grip the same through the medium of a wing nut-equipped bolt 13.

As shown in Figure 3 the clamp 12 interiorly is provided with sharpened prongs 14 that bite or pierce the pole 9 as the clamp 12 is contracted thereabout to positively anchor the clamp to the post 9 against rotative longitudinal shifting movement relative thereto.

The shank 5 has extending therefrom and at substantially right angles thereto a foot bar 15 upon which the foot may be placed for forcing the anchor and pointed end of the pole 9 into the ground. As shown, and if desired, the foot bar 15 has sleeved thereon an extension sleeve 16. Sleeve 16 is provided with an elongated slot 17 which accommodates one end of a key pin 18 that extends transversely through the foot bar 15 to engage the ends of the slot 17 for limiting the shifting movement of the sleeve 16 relative to the foot bar 15. Thus it will be seen that when extended, as suggested by broken lines in Figure 2, sleeve 16 forms an extension of the foot bar 15 and also serves as a handle therefor so that the anchor may be screwed or threaded into the ground if found desirable. Especially will the handle 16 be found serviceable when it is desired to withdraw the anchor and pointed end of the post from the ground.

It is thought that a clear understanding of the construction, utility and advantages of an invention of this character will be had without a more detailed description.

Having thus described the invention what is claimed as new is:

1. An anchor for beach parasol posts and the like, said anchor comprising a body of screw form provided at one end with a shank, and a post-embracing clamp mounted on the shank and extending laterally therefrom, and a combination foot bar and handle extending laterally from the shank, said clamp being provided internally thereof with means for piercing the post to secure the clamp thereon against shifting movement, and a sleeve extension for the foot bar slidably associated therewith.

2. An anchor for a post comprising a rod having a portion shaped to provide a spiral coil, the lower one of which terminates in a point and some of the upper coils being arranged close together for embracing a part of the post, and said rod having a portion extending vertically from the upper coil to form a shank and said rod having an end portion extending at right angles from the upper end of the shank and a clamp attached to the shank portion for attaching the same to the post, said clamp extending in an opposite direction from the right angular part.

JEROME B. SCHROTH.
